INFANT'S SWING

Elwood J. Leep, Palo Alto, Calif.

Application November 6, 1948, Serial No. 149,495

Term of patent 3½ years

(Cl. D5—5)

To all whom it may concern:

Be it known that I, Elwood J. Leep, a citizen of the United States, residing at Palo Alto, in the county of Santa Clara, and State of California, have invented a new, original, and ornamental Design for Infant's Swing, of which the following is a specification, reference being had to the accompanying drawing, forming part thereof.

Fig. 1 is a perspective view of an infant's swing showing my new design.

Fig. 2 is a top plan view of the infant's swing shown in Fig. 1.

Fig. 3 is an end elevational view of the infant's swing shown in Fig. 1.

Fig. 4 is an end elevational view of the infant's swing shown in Fig. 1, taken from the opposite end from that shown in Fig. 3.

Fig. 5 is a side elevational view of the infant's swing shown in Fig. 1.

I claim:

The ornamental design for an infant's swing, as shown.

ELWOOD J. LEEP.
